T. F. WESTON, OF SALEM, MASSACHUSETTS.

Letters Patent No. 63,191, dated March 26, 1867.

IMPROVED MACHINE FOR SHAVING HIDES.

The Schedule referred to in these Letters Patent and making part of the same.

TO ALL PERSONS TO WHOM THESE PRESENTS SHALL COME:

Be it known that I, T. F. WESTON, of Salem, in the county of Essex, and State of Massachusetts, have invented certain new and useful improvements in Machines for Reducing or Shaving Hides to a smooth surface preparatory to the final operation of finishing; and that the following description, taken in connection with the accompanying drawings hereinafter referred to, forms a full and exact specification of the same, wherein I have set forth the nature and principles of my said improvements, by which my invention may be distinguished from all other of a similar class, together with such parts as I claim and desire to have secured to me by Letters Patent.

The present invention consists in certain new and useful improvements in machines for reducing or shaving hides to a smooth surface preparatory to the final operation of finishing. Various devices have heretofore been experimented with for the purpose of accomplishing this result, but in all such cases a knife or scraper has been employed which had but one motion imparted to it, viz, a motion longitudinal with the bed upon which the leather was placed. But this movement has failed to imitate the peculiar manipulation of an operator skilled in this branch of the manufacture, as it is necessary to impart to the cutting tool both a longitudinal and transverse motion, whereas, if solely a forward or longitudinal direction is given to the tool, the effect upon the surface is to tear and roughen its surface and fibres instead of to shave or smooth it. In my improved machine I employ a cutting or scraping tool to which are imparted two motions, one which is longitudinal to the bed upon which the leather is placed, and the other transverse to the same, or nearly so, the result being to produce the drawing cut that is peculiar to the movements of the hand operator, and also accomplish the work with much less time and expense. In the accompanying plate of drawings—

Figure 1 is a plan or top view of my improved machine.

Figure 2 is a side elevation of the same.

Figure 3 is an enlarged vertical section showing certain parts of the machine in detail.

a a, in the drawings, represent an inclined table or platform sustaining a bed-plate, *b b*; this bed-plate to be made of metal, glass, or any other suitable material, and can also be made adjustable in a vertical direction. On the bed-plate *b b* is placed the leather to be scraped or shaved. This is effected by means of a cutter, *c*, which has both a longitudinal or forward movement across the bed-plate *b b*, and a rotary motion imparted to it, as follows: The cutter *c* is attached to a shaft, *d*, having its bearings in a projection of a connecting-rod, *e e*. The connecting-rod *e e* is sustained by an arm, *f*, pivoted at *g* and *h*, and attached to a wheel, *i*, actuated by a shaft, *k*, to which motion can be imparted in any suitable manner; thus the revolution of the wheel *i*, by means of the connecting-rod *e e*, will give a forward and back movement to the cutter *c*, causing the latter to be brought in contact with the leather during its forward or downward movement across the bed-plate *b b*, but relieving or lifting it from the same while returning. The rotary movement is imparted to the cutter *c* by the following means: A pulley, *l*, upon the pivot *m* of the connecting-rod *e e*, conveys motion by means of an endless belt or band, *n*, to the shaft *d*, a belt or band first passing over small guiding-pulleys *o o*.

In the foregoing description and accompanying drawings I have illustrated a circular tool or scraper to which both a forward or longitudinal motion and a rotary movement are imparted, but it will be evident that the same effect can be attained by the use, for instance, of a straight or rectangular-shaped tool which has both a forward or longitudinal movement, and a lateral one transmitted to it by any of the well-known mechanical devices usually employed for such purposes. An endless belt or band of flexible metal having similar motions might also be used, as will be manifest without further explanation.

I claim the use of the cutting, shaving, or scraping tool, having such motions imparted to it by any suitable arrangement of mechanical devices as to produce a drawing cut upon the surface of the leather, as hereinbefore set forth and for the purpose specified.

T. F. WESTON.
